UNITED STATES PATENT OFFICE.

ROBERT H. ANDERSON, OF SAN DIEGO, CALIFORNIA, ASSIGNOR TO RUTH B.
ANDERSON, OF SAN DIEGO, CALIFORNIA.

COMBINED WARDROBE AND BED-RECEPTACLE.

1,110,031.

Specification of Letters Patent.

Patented Sept. 8, 1914.

Application filed February 3, 1913, Serial No. 745,772. Renewed January 29, 1914. Serial No. 815,158.

To all whom it may concern:

Be it known that I, ROBERT H. ANDERSON, a citizen of the United States, and a resident of San Diego, in the county of San Diego, State of California, have invented certain new and useful Improvements in Combined Wardrobes and Bed-Receptacles, of which the following is a specification.

My invention relates to wardrobes which are also adapted for a folding bed receptacle when said bed is not in use and from which said bed may be readily turned down into a room when it is desired for use.

The objects of my invention are, first to provide a simple, economical and easily operated device of the class described; second, to provide one so arranged that it requires only a narrow opening for the entrance and exit of the bed; third, to provide such a receptacle that when the bed is in use it will permit ready passage into and out of a wardrobe; fourth, to provide a device which can be readily installed in wardrobes, closets, recesses, receptacles, etc., without special preparation therefor.

With these and other objects in view as will appear hereinafter, my invention consists of certain novel features of construction, combination and arrangement of parts as will be hereinafter described in detail and particularly set forth in the appended claims, reference being had to the accompanying drawings and to the characters of reference thereon, which form a part of this specification, in which:

Figure 1 is an elevational view of one side of my wardrobe receptacle showing the door thereto and showing the bed folded up in said receptacle by dotted lines, Fig. 2 is an elevational view showing the relative positions of the door and bed and their supporting parts when the bed is being turned out of said receptacle and into the room for use, Fig. 3 is a plan view in section of my receptacle showing a plan view of a bed and door and their supporting parts in position when the bed is out of the receptacle and ready for use.

Similar characters of reference refer to similar parts throughout the several views.

The wardrobe or receptacle 1, door 2, door support 3, and bed support 4, constitute the principal parts of my device.

The wardrobe or receptacle 1 may be any shape desired but preferably rectangular as shown, and in one side is provided a doorway 1^a. This doorway is provided with a door 2, which is pivotally mounted on a door support 3 by means of bearing 2^a, which support, in turn, is pivoted to the top 3^a of the doorway on the bearing 3^a and at the bottom on the bearing 3^b in the floor of said wardrobe or receptacle. These bearings 2^a and 3^b are located in the center of said doorway 1. A sufficient distance to one side of the bearings 3^a and 3^b in the center of the top and bottom walls of the doorway the bearings 4^a and 4^b are located which are similar to bearings 3^a and 3^b and adapted for the pivoted bed support 4. Pivoted to this support 4, by means of bearings 4^c, is the head frame 5 of a folding bed. These supports 3 and 4 are U shaped as shown best in Fig. 2, to allow the bed to pass between the horizontal portion of the same and to set the pivot joints at the place desired for convenient manipulation of said bed relative to the door of the receptacle. This support 4 is provided with a spring 4^d which prevents said support from swinging too far in either direction. The folding bed 6 is foldably mounted on this head frame and may be any folding bed frame desired, but I prefer the construction as shown in the accompanying drawing, described as follows:—The bed frame is mounted on said head frame by means of two tension rods 7, one on each side of said frame and pivotally attached at one of their ends to said head frames. Near the top and at their ends to the bed frame some distance back from the head end near the bottom of said head frame are also pivotally attached the two thrust rods 8 which extend to and are attached to the bed frame between pivotal mountings 9^a of rods 7 and the head end of the bed frame near the bottom of the bed frame when down. This bed frame is supported when down for use by means of the legs 10 which are pivotally mounted to said bed frame.

It is obvious that with this construction, as illustrated and described, there is provided a combined wardrobe and bed receptacle that is simple of construction and easily operated; that when the bed is in use there is ready access to the wardrobe; that the bed

may be readily shifted into and out of said receptacle that the doorway may be narrow; and that the receptacle may be narrow.

Having thus described my invention, what I claim as new and desire to secure by Letters Patent is:—

1. A combined wardrobe and bed receptacle comprising a receptacle provided with a doorway, a U-shaped support pivoted centrally in said doorway and a door pivotally mounted thereon, another U shaped support pivoted in said doorway adapted for attaching a folding bed thereto.
2. A combined wardrobe and bed receptacle comprising a receptacle provided with a doorway, a bed support pivotally mounted to the top and bottom walls and near the center of said doorway, a door support pivotally mounted centrally in said doorway to the top and bottom walls thereof, and a door pivotally mounted on said support adapted to be reversed on said support and close said opening on its inner or outer surfaces.
3. A combined wardrobe and bed receptacle comprising a wardrobe provided with an opening therein, a support pivotally mounted in said opening to the top and bottom walls near the center thereof, another support pivotally mounted centrally in said opening to the top and bottom walls thereof and a door pivotally mounted to said support near the side so as to allow the door to reverse around said sup-

port and close said opening near the inner 35 surface or the outer surface of said wardrobe.

4. In a combined wardrobe and bed receptacle the combination of a wardrobe provided with an opening in the wall thereof 40 and a plurality of supports pivotally mounted in said opening to the top and bottom walls near the center thereof, the one adapted for the pivotal mounting of a folding bed and the other for a door.

5. In a combined wardrobe and bed receptacle the combination of a wardrobe or receptacle provided with an opening in the one side thereof, a U shaped support pivotally mounted to the top and bottom walls 50 of said opening adapted to swing in said opening, bearings mounted on the vertical portion thereof adapted to be attached to the head-board of a bed, another U shaped support similarly mounted in said opening, a plurality of collars mounted on said support, a plurality of bearings mounted thereon and a door rigidly mounted near its one side on said bearings adapted when swung on said support to close said opening at its inner or outer side.

In witness whereof, I have hereunto subscribed my name in the presence of two subscribing witnesses.

ROBERT H. ANDERSON.
